UNITED STATES PATENT OFFICE.

GEORGE T. CONRATH, OF BOWLING GREEN, OHIO.

STOPCOCK.

1,416,173.

Specification of Letters Patent. Patented May 16, 1922.

Application filed March 20, 1918. Serial No. 223,624.

To all whom it may concern:

Be it known that I, GEORGE T. CONRATH, a citizen of the United States, residing at Bowling Green, in the county of Wood and State of Ohio, have invented new and useful Improvements in Stopcocks, of which the following is a specification.

This invention relates to stop cocks, and has for its primary object to produce a stop-cock in which the plug will be firmly retained on its seat, but readily turned without danger of breaking either the plug or the casing therefor.

Other objects and advantages will appear as the nature of the invention is better understood, reference being had to the accompanying drawings, in which,

Figure 1 is an approximately vertical longitudinal sectional view through a stop-cock constructed in accordance with this invention.

Figure 2 is a top plan view of the same.

Figure 3 is a view of the removable bridge piece.

Figure 4 is an approximately central longitudinal sectional view through a modification.

Figure 5 is a top plan view of the same.

Figure 6 is an end view, the bridge piece being removed.

Figure 7 is a perspective view of the bridge piece employed.

Figure 8 is a side elevation, partly in section of a further modification.

Figure 9 is a sectional view through a still further modification.

Figure 10 is a similar view of a further modification.

Figure 11 is a top plan view of the same.

Figure 12 is an elevation of the valve plug.

The casing for the valve or stop-cock is indicated by the numeral 15 and is provided with alining passages to which the ends of the usual pipes are connected. The valve or plug chamber extends entirely through the casing, and is indicated by the numeral 16.

The chamber is flared or gradually decreased in cross sectional diameter from the upper to the lower ends thereof so as to snugly receive therein the tapering plug valve 17. The valve, at its reduced end is integrally formed with a lug 18, which, of course, is arranged outward of the casing 15, and this lug provides the turning element for the plug valve 17. The valve 17, upon its wider

end is centrally formed with an outstanding enlargement in the nature of a boss 19. The casing 15, at the upper face thereof is provided with a pair of spaced alining threaded openings 20 which are adapted to register with openings 21 provided in the ends of an arched bridge piece 22. The alining openings in the bridge piece and in the casing receive the threaded stems 23 of bolt members 24 whereby the bridge piece 22 is removably secured to the valve casing. The bridge piece is centrally provided with a threaded opening 25 receiving therein a threaded member 26, the same having its inner end rounded as at 27 and contacting centrally with the boss 19. The outer end of the member 26 is squared or otherwise shaped to receive or arrange a similar element whereby the said member 26 may be turned to force the same into contact with the boss on the widened end of the valve to force the said valve into tight engagement with the walls of the seat of the chamber 17.

In Figures 4 to 7 of the drawings I have illustrated a slight modification, the valve casing 28 and the valve 29 being substantially similar to that previously described, except with the casing 28, upon its upper surface is provided with an annular extension 30 that has, upon its upper edge diametrically opposed outstanding flanges 31—31, and spaces 32 between the flanges. Each of the flanges, upon its inner face is approximately centrally formed with a depression 33. The bridge piece is indicated by the numeral 34 and has its ends provided with downturned portions 35 formed with in-turned lugs 36. The lugs are spaced so that the same may be received in the spaces 32 between the flanges 31 and thereafter the bridge piece may be turned to bring the lugs 36 under the flanges 31 and also to bring the said lugs into the depressions 33 which provide pockets for the said lugs. The bridgepiece 34 is centrally provided with a threaded opening receiving therein a threaded element 37 which contacts with the boss 38 on the widened end of the plug valve 29.

In Figure 8 the construction is substantially similar to that illustrated in Figures 1, 2 and 3 of the drawings, the arched bridge member 39 being connected to the upper face of the valve casing 40 by removable bolts 41. The bridge is centrally provided with a comparatively large threaded opening 42 which receives therein a threaded member 43

having a turning head 44. The member 43 has its inner end provided with a pocket 45 within which is received a boss 46 on the plug valve 47.

5 In Figure 9 the tapering plug valve 50 has its reduced end centrally provided with a lug 51 which is of a greater length than the lugs employed on the plug valves previously described, but in other respects the 10 valve 50 is similar to the valves previously described. The valve casing 52, upon its upper end is provided with an annular extension 53 having exterior threads, and these threads are engaged by inner threads provided upon a flange 54 on the ends or periphery of the bridge member 55. The 15 bridge member, in this instance is in the nature of a cap and is centrally provided with a threaded opening through which 20 passes a threaded binding element 56 that engages with the boss 57 on the widened end of the plug valve 50. The lower end of the casing 52 is provided with a threaded annular extension 52' engaged by a flanged 25 nut 53'. The nut is provided with a central round opening through which the cross sectional round portion of the stem or lug 51 passes, and the said nut has arranged there- 30 in an annular flanged gasket 54' which contacts with a packing 55' forcing the same against the lug 51 and the under face of the valve casing inward of the annular member 52'.

In Figures 10 and 11 the plug valve 58 35 is substantially similar to those previously described. The cock or valve casing 59, upon its upper face is provided with an annular extension 60 having inwardly extending spaced flanges 61—61 and providing 40 spaces 62 between the said flange. The arched bridge piece is indicated by the numeral 63 and has its ends provided with outstanding portions which may be termed lugs and which are indicated by the numerals 64. 45 The bridge is so arranged as to permit of the lugs thereof being passed through the spaces 62 below the flanges 61 and thereafter turned to position the said lugs centrally of the flanges and permit of the lugs 50 being received in depressions 65 which are arranged centrally on the inner faces of the lugs 61. The bridge piece 63 is centrally provided with a threaded opening through which passes a threaded binding element

66 that has its inner and rounded end contacting with the boss 67 on the upper and widened end of the plug valve 58.

66 In all instances it will be noted that the valve extends entirely through the valve casing and has its reduced end provided 60 with a lug designed to receive a pivot or other instrument whereby the valve may be operated. All of the plugs, upon their widened ends are provided with bosses and 65 all of the bosses are contacted with adjustable elements to force the valves primarily in their seats. The valves, while properly engaging with their seats may be easily turned and from experience I have found that this construction prevents the entrance 70 of frost or rust between the valve and casing so that neither the plugs nor casing can be injured from such causes and will amply withstand the pressure to which they are subjected.

75 It is believed, from the foregoing description that the advantages of the construction will be understood and appreciated without further detailed description, it being understood that the valve is self grinding.

Having thus described the invention, what I claim is:

A valve casing having a tapered opening extending therethrough and providing a valve seat, a tapered plug valve, the ground surface of which directly contacts with the seat, permitting of locking engagement, said valve having its reduced end centrally provided with an outstanding lug, said casing 85 at the widened end of the opening therein being formed with an extension having spaced flanges on the ends thereof, said flanges, upon their inner faces being formed with recesses intermediate of the openings 90 between the flanges, a bridge member including downwardly and inwardly extending lugs proportioned for reception between the flanges and for reception within the depressions, upon turning the bridge about the 95 longitudinal axis of the plug, and an element threaded through the bridge and acting to produce an inward thrust on the larger end of the plug for seating the latter, and an outward thrust between the lugs and 100 the recessed portions of the flanges.

105 In testimony whereof I affix my signature.

GEORGE T. CONRATH.
